[57] CLAIM

The ornamental design for a fecal occult blood test kit, substantially as shown and described.

DESCRIPTION

FIG. 1 is a perspective view of a fecal blood test kit embodying my ornamental design in which cover tab components are in a closed position;

FIG. 2 is a perspective view similar to FIG. 1 but illustrating the cover tab members thereof in open position; and

FIG. 3 is a top plan view thereof shown with two cover tab members closed and one open.

The sides which are not shown and the bottom surface are substantially planar and unornamented.
